UNITED STATES PATENT OFFICE

2,109,439

CHLORINATOR

Clair V. Swearingen, Chattanooga, Tenn.

Application June 1, 1937, Serial No. 145,891

5 Claims. (Cl. 210—28)

The invention relates to a chlorinator and more especially to a manually controlled pressure type gas feed chlorinator.

The primary object of the invention is the provision of an apparatus of this character, wherein chlorine gas or other gases for bleaching flour and other material or for sterilizing of water and treatment of sewage and industrial wastes will be delivered to the vicinity of application and where the chlorine can be mixed with water in any desired proportion.

Another object of the invention is the provision of a device of this character, wherein the feed of the chlorine under pressure can be readily and easily regulated to vary the strength of such chlorine or other gases utilized for bleaching, sterilization or other purposes, the device being of novel construction.

A further object of the invention is the provision of a device of this character, which is simple in its construction, thoroughly reliable and effective in operation, compact, manually controlled, and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is an elevation partly in section of the device constructed in accordance with the invention.

Figure 2 is an enlarged fragmentary top plan view showing the indicator for regulating the feed of chlorine or other gases.

Figure 3 is a sectional view on the line 3—3 of Figure 2 looking in the direction of the arrows.

Similar reference characters indicate corresponding parts throughout the several views in the drawing.

Referring to the drawing in detail, A designates generally a case which is provided with a door, a portion thereof being shown at B having a transparent panel C. Adapted to be disposed within and depending a distance in said case A is a substantially U-shaped glass tube 5 for the carrying of water or a solution 6 therein. This tube 5 at one of its vertical legs is joined with a valve casing 7 for a hand operable valve (not shown), the stem 8 of which is fitted with a hand wheel 9 while the other leg is joined by a coupling hose 10 with a T union 11 connected to

and between a flow reducer 12 and a discharge hose 13, respectively. This flow reducer 12 is in the form of an orifice and has connection with a four-way union 14 at the branch 15 thereof, the branch 16 having connection with the valve 5 casing 7. The branch 17 has communication with a pressure gauge 18 while the branch 19 has communication with a gas control valve casing 20 which is also in communication through a tube 21 with a chlorine or other gas pressure tank 22 equipped with a hand operated cut-off valve 23 as is usual, the gas valve mechanism within the casing 20 being hereinafter described.

The casing 20 is formed interiorly thereof with a partition 24 provided with a needle valve opening 25 and a valve seat 26, respectively, for a needle valve 27. This needle valve 27 is fitted with an internally threaded socketed cap 28 adjustably threaded at 29 with the casing 20 so that by the turning of the cap the valve 27 will move 15 toward and away from the opening 25 and when engaged therein will become seated at 26 in said casing. In this manner the chlorine or other gas flow from the tank 22 will be regulated for admission to the tube 13 in the working of the 20 25 device.

Fitted by clips 30 with the casing 20 is a half circular dial 31 which projects laterally to one side following a horizontal plane with respect to said casing 20 and this dial is provided with 30 indicia presenting independent scales or calibrations 32 and 33, respectively, as well as temperature indications 34 of high and low degree, the low temperature indication being associated with the scale 32 while the high temperature indication 35 is in association with the scale 33 for a purpose presently described.

Fitted for rotary adjustment upon the cap 29 through engagement of a clamp terminal 35 about the same is a pointer 36 for correct setting 40 thereof and accurate cooperation of the same with the scales 32 and 33, respectively, in the use of the device. When the needle valve 27 is closed, the pointer 36 should coincide with the zero mark of the scale 33 and in this manner 45 indicating the fact that the said valve is in closed position. The clamp 35 includes a releasing screw 37 permitting the pointer 36 to be adjusted when the occasion requires for accuracy in the reading of the dial through coaction of said 50 pointer with the scales 32 and 33 on the dial.

The cap 28 and the valve 27 carried thereby have in association therewith a hand crank or handle 38 for manual turning of said cap and valve in regulating the feed of gas from the

tank 22 through the tube 5 on the opening of the valve in the casing 7 or directly through the tube 13.

In the use of the chlorinator, either during high or low temperatures, it is required that the valve 27 be adjusted. When the temperature is low the said valve 27 must be opened more than it need be opened when the temperatures are higher to effect the same pressure reading on the pressure gauge 18 and thus to have the pointer 36 indication consistent, it is required that a reading of the scale 32 present on the dial 31 be had when colder temperatures prevail while a reading of the scale 33 in cooperation with the pointer 36 is had when higher temperatures prevail and thus accuracy in the adjustment of the valve 27 can be assured accordingly thereto.

In the operation of the device the gas from the tank 22 in the feed thereof to the tube 13 can be had by setting the valve 27 and on opening the valve within the casing 7 the flow of gas will by-pass the reducer 12 through the tube 5 containing water or solution 6 and such gas passes through the water or solution 6 in the tube 5 mixing with the latter and finally passing into the tube 13 and discharged therefrom for application. The pressure gauge 18 and the pointer 36 cooperating with the scales 32 and 33 on the dial 31 give the pounds pressure of the gas being discharged through tube 13 from the tank 22, the pressure gauge 18 being a check on the pointer 36 in cooperation with the scales 32 and 33 in the working of the device.

The pressure gauge 18 is indicative of the gas pressure in tube 5 while the pointer 36 coacting with the scales 32 and 33 indicates pressure at the reducer 12. The tank 22 containing chlorine gas can be obtained commercially from many chemical plants as will be understood. As has been stated, the tank is provided with the cut-off valve 23 for controlling the discharge of the gas therein and said tank, as is customary, is placed on the weighing scales 39.

As soon as the gas valve 27 is open, the water level in the U pipe 5 will move when the valve or cock 7 is opened. As the gas goes through the U tube 5, the liquid in the U tube will move to a vertical position on the right leg where the gas will pass the liquid in the said tube and then the liquid will drop back to the original position and the liquid will pulsate back and forth as long as there is gas going through the said tube 5 and the valve or cock 7 is open. This U tube 5 is used only for setting the pointer 36 on zero and for by-passing the gas through the said tube 5 so that the water level will show no definite water pressure.

What is claimed is:

1. In a chlorinator apparatus, a gas tank having a valved outlet for controlling discharge of gas therefrom, a four-way union having a branch connection with said valved outlet, a discharge tube leading from another branch of said union and having a reducer, a substantially U-shaped tube connected with another branch of said union and with the discharge tube, respectively, the connection between both tubes being located at the outlet side of the reducer, a pressure gauge connected with the remaining branch of said union, a needle valve arranged in the branch leading from said tank, a calibrated dial supported next to the needle valve, an indicator coacting with the needle valve and traversing said dial, and means adjustably connecting the indicator with the needle valve.

2. In a chlorinator apparatus, a gas tank hav-

ing a valved outlet for controlling discharge of gas therefrom, a four-way union having a branch connection with said valved outlet, a discharge tube leading from another branch of said union and having a reducer, a substantially U-shaped tube connected with another branch of said union and with the discharge tube, respectively, the connection between both tubes being located at the outlet side of the reducer, a pressure gauge connected with the remaining branch of said union, a needle valve arranged in the branch leading from said tank, a calibrated dial supported next to the needle valve, an indicator coacting with the needle valve and traversing said dial, and means adjustably connecting the indicator with the needle valve.

3. In a chlorinator apparatus, a gas tank having a valved outlet for controlling discharge of gas therefrom, a four-way union having a branch connection with said valved outlet, a discharge tube leading from another branch of said union and having a reducer, a substantially U-shaped tube connected with another branch of said union and with the discharge tube, respectively, the connection between both tubes being located at the outlet side of the reducer, a pressure gauge connected with the remaining branch of said union, a needle valve arranged in the branch leading from said tank, a calibrated dial supported next to the needle valve, an indicator coacting with the needle valve and traversing said dial, means adjustably connecting the indicator with the needle valve, and means for turning the needle valve.

4. In a chlorinator apparatus, a gas tank having a valved outlet for controlling discharge of gas therefrom, a four-way union having a branch connection with said valved outlet, a discharge tube leading from another branch of said union and having a reducer, a substantially U-shaped tube connected with another branch of said union and with the discharge tube, respectively, the connection between both tubes being located at the outlet side of the reducer, a pressure gauge connected with the remaining branch of said union, a needle valve arranged in the branch leading from said tank, a calibrated dial supported next to the needle valve, an indicator coacting with the needle valve and traversing said dial, means adjustably connecting the indicator with the needle valve, means for turning the needle valve, and liquid confined within said last-mentioned tube.

5. In a chlorinator apparatus, a gas tank having a valved outlet for controlling discharge of gas therefrom, a four-way union having a branch connection with said valved outlet, a discharge tube leading from another branch of said union and having a reducer, a substantially U-shaped tube connected with another branch of said union and with the discharge tube, respectively, the connection between both tubes being located at the outlet side of the reducer, a pressure gauge connected with the remaining branch of said union, a needle valve arranged in the branch leading from said tank, a calibrated dial supported next to the needle valve, an indicator coacting with the needle valve and traversing said dial, means adjustably connecting the indicator with the needle valve, means for turning the needle valve, liquid confined within said last-mentioned tube, and a valve located in the last-mentioned tube adjacent to its connection with the said union.
